[57] ABSTRACT

An amusement device challenging the dexterity and skill of players in the progressive advancement of fragile playing pieces along a chute without dismemberment of the playing piece to the embarrassment of the player. A suitable playing piece may be hollow egg-shaped and formed of parts held delicately assembled and enclosing a heavy loose part, preferably of non-spherical shape, effective to fall apart if the playing piece is not carefully maneuvered in play. The chutes are equipped with movable barriers manipulatable by the players to control advance of the individual playing pieces.

GAME DEVICE FOR MANIPULATING SEPARABLE PLAYING PIECES

This invention relates to amusement devices, and more particularly to a game of skill for two or more players utilizing a fragile playing piece which may be advanced progressively along a chute-like passageway without dismemberment provided adequate playing skill is employed.

An illustrative embodiment of the invention includes a plurality of chute-like passages supported in an inclined or upright position and each equipped with a plurality of movable barriers manipulatable in succession to advance a fragile playing piece from a starting to a finish position. Typically, the playing chutes are supported about the periphery of an upright main body terminating at its lower end in separate receiving receptacles for the individual playing pieces. Levers projecting through the sides of the chutes are individually manipulatable to release the playing piece from one portion of the chute to the next lower portion. Each barrier includes biasing means for holding it normally in position to block passage of the playing piece unless deliberately manipulated.

The playing piece may comprise an irregularly shaped hollow member, such as a simulated egg shell, parts of which are delicately held assembled, as by snap fit. A non-spherical heavy article freely movable internally of the playing piece greatly increases the unpredictability of the movement of the playing piece and as is equally true of the differently contoured opposite ends of the playing piece with the result that the piece may come to rest in innumerable different positions additionally augmented by the position therein of the irregular shape of the captive mass. The object of the players is to have their playing piece reach the outlet end of the chute first without dismemberment. Dismemberment of any playing piece disqualifies that player from further play.

Accordingly, it is a primary object of this invention to provide a simple, rugged and intriguing amusement device of novel construction.

Another object of the invention is the provision of a unique simple device challenging the skill and dexterity of a plurality of players utilizing individual playing pieces subject to dismemberment if not skillfully maneuvered in play.

These and other more specific objects will appear upon reading the following specification and claims and upon considering in connection therewith the attached drawing to which they relate.

Referring now to the drawing in which a preferred embodiment of the invention is illustrated:

FIG. 1 is a side elevational view of an illustrative embodiment of the invention;

FIG. 2 is a top plan view of FIG. 1 on an enlarged scale with portions of the device broken away to show constructional details;

FIG. 3 is a cross-sectional view taken along line 3—3 on FIG. 2;

FIG. 4 is a perspective view of a typical playing piece in assembled condition;

FIG. 5 is a cross-sectional view taken along line 5—5 on FIG. 4; and

FIG. 6 is a perspective view of one of the movable barriers.

Referring more particularly, initially, to FIGS. 1, 2 and 3, there is shown an amusement device, designated

generally 10, incorporating the principles of this invention. Device 10 has a deep, saucer-like base 11 supporting a rigid tubular main body 12 having a plurality of chute-like passages 13 extending vertically of each outer sidewall. As clearly shown by way of example, chutes 13 are generally rectangular in cross section and have an inlet opening 14 at their upper end and an outlet 15 at their lower end. The saucer-like base 11 is provided with radial partitions 16 (FIG. 2) between adjacent chutes confining the playing piece from each chute to the area between the partitions. As herein shown, the sidewalls of chutes 13 are molded integral with the main body, the front of these chutes being closed by an individual cover plate 18 having inturned flanges 19 along either lateral edge slidably engaged in and retained captive by grooves 20 of the chute sidewalls. These cover plates may be opaque, as 18, or transparent as 18'.

The interior of each chute 13 is subdivided into separate portions by movable barriers 25 having the constructional features best illustrated in FIG. 6. These barriers include a scoop-like inner end 26, one or more resilient tangs 27,27 and an operating handle 28. The barriers also include at least one tang 29 and possibly a second tang 30 projecting in opposite directions from the mid-portion of the barrier and cooperating with the adjacent surfaces of the chute sidewalls to hold the barrier assembled within a slot 32 in the chute sidewall. Slots 32 are closed at their inlet ends by cover plate 18 and so shaped as to permit but limited pivotal movement of the barrier between the full and dotted line positions thereof shown in FIG. 3. If tangs 30 interfere with the free movement of the barriers they may be omitted since tang 29 and the resilient fingers or tangs 27 are sufficient to hold the barriers in position. The resilient fingers 27 urge the barriers to their normal full line position illustrated in FIG. 3.

The barriers 25 are preferably arranged in staggered echelon relation and are so disposed relative to one another that the release of the playing piece from an upper position onto a lower barrier blocks the passage of the playing piece against further advance along the chute until the lower barrier is manipulated by the player.

Referring to FIGS. 4 and 5, there is shown an illustrative playing piece in the form of a hollow egg-shaped member 35 formed in two halves 36,37 having overlapping edges 38,39 so shaped as to have a delicate retaining action effective to hold parts 36,37 assembled if the playing piece is manipulated with care. However, a sudden jar or impact action is effective under most circumstances to separate the two halves and to permit an internal component 40 to escape. Component 40 is representative of an egg yolk and is preferably of irregular or non-spherical shape with the result that it is likely to tumble irradically and unpredictably within the playing piece and may impart sufficient force to separate the parts, particularly if it strikes the parts in certain areas. This unpredictable random action of component 40 adds greatly to the amusement and excitement of play and can thwart even a skillfully executed play.

Play is usually conducted using any suitable spinner such as spinner 45 fixed to the top of device 10 and having a freely rotating needle 46 movable past sectors 47 each marked with suitable indicia indicating to the player whether or not he may proceed to move his playing piece and, if so, by a stated number of positions of

advance. Each player starts with his own distinctively colored playing piece positioned on the uppermost one of the barriers in his selected playing chute. The player first advancing his playing piece through the outlet without dismemberment is declared the winner. Any player whose playing piece is dismembered in play is immediately disqualified.

While the particular amusement device herein shown and disclosed in detail is fully capable of attaining the objects and providing the advantages hereinbefore stated, it is to be understood that it is merely illustrative of the presently preferred embodiment of the invention and that no limitations are intended to the detail of construction or design herein shown other than as defined in the appended claims.

I claim:

1. An amusement device for use by more than one player, said device having a main body provided with a separate playing chute for each player steeply inclined upwardly from the outlet end thereof, each of said chutes including a plurality of barriers movably supported at spaced intervals therealong and each including actuating means manipulatable by the player to release a playing piece for gravity movement into contact with the next lower one of said barriers, and a separate playing piece for each of said chutes, each of said playing pieces being formed in a plurality of parts and including means for holding said parts releasably assembled and responsive to light impact force to become dismembered if allowed to move along one of said chutes without due care on the part of a player.

2. A device as defined in claim 1 characterized in that said chutes are arranged in edge to edge relation.

3. A device as defined in claim 1 characterized in that

said chutes are arranged about a common upright axis.

4. A device as defined in claim 3 characterized in that said main body includes receptacle means at the base of said chutes for receiving the player piece from the respective chutes as the same issues from the respective chute outlets.

5. A device as defined in claim 1 characterized in that said movable barriers each have individual operator means therefor separately manipulatable by a player to effect transfer of a playing piece from one portion of a given chute to the next lower portion of the same chute.

10 6. A device as defined in claim 5 characterized in that said movable barriers are staggered in echelon along said chutes.

15 7. A device as defined in claim 1 characterized in that said playing pieces are hollow and include a heavy object held captive but free to tumble from place to place interiorly of the playing piece so long as the same remains assembled.

8. A device as defined in claim 7 characterized in that said playing piece is egg-shaped and formed in two principal parts.

20 9. A device as defined in claim 7 characterized in that said heavy object within said playing piece is non-spherical in contour.

25 10. A device as defined in claim 1 characterized in that said movable barriers are integral and include means for normally holding the same in position to hold the playing piece captive in the adjacent area of the chute until manually moved to a position releasing the playing piece for gravity movement onto the next lower one of said movable barriers.
